(57) **CLAIM**

The ornamental design for a sounder housing, substantially as shown and described.

DESCRIPTION

FIG. 1 is a front isometric view of a sounder housing; FIG. 2 is a rear isometric view thereof; FIG. 3 is a right side elevational view thereof, the left side elevational view being the mirror image of the right side elevational view;

FIG. 4 is a rear elevational view thereof;

FIG. 5 is a top plan view thereof; and,

FIG. 6 is a bottom plan view thereof.

The broken lines illustrate portions of the sounder housing, that form no part of the claimed design.
